DESIGN FOR A SHOE

Harry Le Roy Sutcliffe, New York, N. Y.

Application December 19, 1941, Serial No. 104,739

Term of patent 3½ years

To all whom it may concern:

Be it known that I, Harry Le Roy Sutcliffe, a citizen of the United States of America, residing in New York city, county of New York, and State of New York, have invented a new, original, and ornamental Design for a Shoe, of which the following is a specification, reference being had to the accompanying drawing, forming part thereof.

The figure on the drawing is a front perspective view of a shoe showing my new design, the opposite side presenting substantially the same appearance as the side shown.

I claim:

The ornamental design for a shoe, substantially as shown and described.

HARRY LE ROY SUTCLIFFE.
